UNITED STATES PATENT OFFICE.

SARAH A. BISHOP, OF PITTSBURG, PENNSYLVANIA, ADMINISTRATRIX OF THOMAS S. BISHOP, DECEASED.

VALVE.

SPECIFICATION forming part of Letters Patent No. 415,699, dated November 26, 1889.

Application filed July 23, 1889. Serial No. 318,382. (No model.)

To all whom it may concern:

Be it known that I, SARAH A. BISHOP, a citizen of the United States, residing at Pittsburgh, in the county of Allegheny and State of Pennsylvania, administratrix of the estate of THOMAS S. BISHOP, late a citizen of the United States, residing at Pittsburgh, in the county of Allegheny and State of Pennsylvania, deceased, (as by reference to the duly certified copy of letters of administration hereto annexed will more fully appear,) do hereby declare that THOMAS S. BISHOP invented a new and useful Improvement in Valves, of which the following is a specification.

This invention relates to improvements in valves; and it consists in certain novel features hereinafter described and claimed.

In the accompanying drawings, Figure 1 is a sectional view of a valve provided with the improved devices. Fig. 2 is a detail sectional view showing the manner of securing the valves to the stem.

The shell A is of the usual construction, and is provided with an inlet-opening B, an outlet-opening C, and a diagonally-arranged partition D, having a central opening E. Within the opening E, I secure the bushing or ring F, having its inner edge beveled, so as to form a valve-seat. The shell A is provided at one side with an opening G, and this opening is covered with a cap H, which is secured to the shell by means of bolts passed through the edge of the cap and the annular flange I of the shell. This cap is provided with a central opening J, through which the valve-stem passes, and on its inner side it is provided with the annular rib K, which is beveled to form a valve-seat, and on its outer side is provided with a chamber L, forming a stuffing-box, which is closed by a gland M. From one side of the cap projects a frame N, which is provided with a bearing O, and in the said bearing the valve-stem P is mounted, the said stem being threaded, so that it can be readily moved longitudinally in the said bearing. The valve-stem is provided with a hand-wheel Q at its outer end and extends through the gland M and the central opening J of the cap G. The inner end of the valve-stem is provided with an annular enlarge-

ment R, and near the inner end I form on the valve stem the screw-threads S. A small valve T is secured rigidly on the valve-stem and is adapted to rest upon the valve-seat formed by the annular rib K. The said valve consists of a disk or circular plate and a nut or collar U, formed integral with said disk and internally threaded, so as to engage the screw-threads S and thereby secure the said valve on said stem.

A valve V, of larger diameter than the valve T, is swiveled to the end of the valve-stem and is adapted to rest on the valve-seat formed by the bushing F. The said valve consists of a disk or circular plate W, a spindle or stem X, formed integral therewith and extending therefrom to the central opening in the partition D, and engaging suitable bearings in the guide Y, formed on said partition, and a ring Z, formed integral with the disk and projecting therefrom past the end of the valve-stem and internally threaded. This ring Z is engaged by a collar a, adapted to slide on the valve-stem and turning up toward the annular enlargement R, so as to secure the said valve V to the valve-stem.

By the use of a valve constructed in accordance with this invention a new supply of packing may be placed in the chamber L without interfering with the operation of the valve. In operation the larger valve is opened or drawn from its seat by properly operating the valve-stem, and this operation will draw the smaller valve against its seat, so that it will surround the base of the stuffing-box and prevent the steam escaping through the packing. The gland and the packing can then be easily removed and fresh packing easily substituted. By this device the packing will last for a longer period of time than heretofore, as it is cut off from the action of the steam or other fluid passing through the valves, as will be readily understood. The construction of this valve is such that no packing is required in the interior of the valve casing or shell, and the passage therethrough is left almost entirely unobstructed.

No broad claim is made in this application to a valve-stem carrying two valves, as such devices have heretofore been provided. In this device, however, an ordinary valve-stem

can be employed, and the construction of the valves is such as to simplify and cheapen the device.

Having described the invention, what is claimed, and desired to be secured by Letters Patent, is—

The combination, with the shell having an internal partition provided with the guide Y and the valve-seat F, and the cap H, having a valve-seat K on its inner side and a stuffing-box on its outer side, of the valve-stem passing through the cap and having the screw-threads S, and provided at its inner end with the annular enlargement R, the valve T, having the nut U engaging the screw-threads S, the said valve being adapted to

rest against the valve-seat K, and the valve V, having a ring Z encircling the annular enlargement R, and an integral stem X, passing through the guide Y, as specified. 20

In testimony that I claim the foregoing as the invention of THOMAS S. BISHOP, I have hereunto affixed my signature in presence of witnesses.

SARAH A. BISHOP,
*Administratrix of Thomas S. Bishop,
deceased.*
